(57) **CLAIM**

The ornamental design for a table, as shown and described.

DESCRIPTION

FIG. 1 is a top, front, upper perspective view of a table embodying my new design;

FIG. 2 is a top plan view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top, front, upper perspective view of a second embodiment of a table embodying my new design;

FIG. 8 is a top plan view thereof;

FIG. 9 is a left side elevational view thereof;

FIG. 10 is a right side elevational view thereof;

FIG. 11 is a front elevational view thereof;

FIG. 12 is a rear elevational view thereof;

FIG. 13 is a top, front, upper perspective view of a third embodiment of a table embodying my new design;

FIG. 14 is a top plan view thereof;

FIG. 15 is a left side elevational view thereof;

FIG. 16 is a right side elevational view thereof;

FIG. 17 is a front elevational view thereof;

FIG. 18 is a rear elevational view thereof;

FIG. 19 is a top, front, upper perspective view of a fourth embodiment of a table embodying my new design;

FIG. 20 is a top plan view thereof;

FIG. 21 is a left side elevational view thereof;

FIG. 22 is a right side elevational view thereof;

FIG. 23 is a front elevational view thereof;

FIG. 24 is a rear elevational view thereof;

FIG. 25 is a top, front, upper perspective view of an fifth embodiment of a table embodying my new design;

FIG. 26 is a top plan view thereof;

FIG. 27 is a left side elevational view thereof;

FIG. 28 is a right side elevational view thereof;

FIG. 29 is a front elevational view thereof; and,

FIG. 30 is a rear elevational view thereof;

The broken line representations of a zipper in FIGS. 6, 12, 18, 24, and 30 are for the purpose of illustration only, and form no part of the claimed design.
